UNITED STATES PATENT OFFICE

CHARLES A. MEALY, OF WEST BARRINGTON, RHODE ISLAND, ASSIGNOR TO THE HADLEY COMPANY, INC., OF PROVIDENCE, RHODE ISLAND, A CORPORATION OF RHODE ISLAND

DESIGN FOR A WATCH BRACELET

Application filed October 23, 1930. Serial No. 37,358. Term of patent 3½ years.

To all whom it may concern:

Be it known that I, CHARLES A. MEALY, a citizen of the United States of America, residing in West Barrington, in the county of Bristol and State of Rhode Island, have invented a new, original, and ornamental Design for Watch Bracelet, of which the following is a specification, reference being had to the accompanying drawings, forming part thereof.

Fig. 1 is a plan view of a watch bracelet showing my new design; and

Fig. 2 is an edge view of the bracelet.

I claim:

The ornamental design for a watch bracelet as shown.

Signed by me at West Barrington, in the county of Bristol and State of Rhode Island, this 14th day of October, 1930.

CHARLES A. MEALY.
